UNITED STATES PATENT OFFICE.

CLIFTON I. MILLER, OF BRISTOL, TENNESSEE.

LAMP-BURNER.

No. 802,055.

Specification of Letters Patent.

Patented Oct. 17, 1905.

Application filed June 7, 1905. Serial No. 264,194.

To all whom it may concern:

Be it known that I, CLIFTON I. MILLER, a citizen of the United States, residing at Bristol, in the county of Sullivan and State of Tennessee, have invented a new and useful 5 Lamp-Burner, of which the following is a specification.

This invention relates to lamp-burners.

The object of the invention is to provide a 10 lamp-burner adapted by a change in location of one of its parts to burn either a relatively wide or relatively narrow wick or to accommodate shades of different sizes, and, further, by adapting it for ready use in connection 15 with one or more fonts to extend its range of usefulness.

With the above and other objects in view, as will appear as the nature of the invention is better understood, the same consists in the 20 novel construction and combination of parts of a reversible lamp-burner, as will be herein-after fully described and claimed.

In the accompanying drawings, forming a part of this specification, and in which like 25 characters of reference indicate corresponding parts, Figure 1 is a view in vertical longitudinal section of a lamp-burner constructed in accordance with the present invention. Fig. 2 is an inverted plan view of the base- 30 plate of the gallery, the collar being omitted. Fig. 3 is a view in side elevation, exhibiting more particularly the relative sizes of the two collars employed. Fig. 4 is a view in side elevation of the cone.

35 Referring to the drawings, 1 designates the gallery, which may be of the usual or any preferred construction and is combined with a base-plate 2 either by being formed integral therewith or secured thereto. The gallery, 40 members 3 are herein shown as ornamented by open-work; but this is not essential, as they may be plain, if preferred.

Combined with the under side of the base-plate is a collar 4, having, as usual, a threaded 45 extension 5 to engage with the collar of the lamp-font, the collar 4 being combined with the base-plate by providing the former with a plurality of fingers 6, designed to engage slots or orifices 7, the ends of the fingers being bent over upon the upper side of the base-plate, as clearly shown in Fig. 1. Combined with the upper side of the base-plate 50 is a second and larger collar 8, having a threaded extension 9 to engage with the collar of the lamp-font and is also provided

with fingers 10, which are designed to engage slots or orifices 11, the ends of the fingers being bent under against the base, as clearly shown in Fig. 1, thereby to hold the collar firmly in position. As will be seen by reference to Fig. 1, the extension 9 is of greater diameter than the extension 5, thus to adapt the burner for use in connection with lamps of different sizes. Secured in any suitable manner within the extensions 5 and 9 is a 60 wick-tube 12, that end engaging the extension 5 being constricted or smaller in diameter than the end engaging the extension 9, thereby to permit of the use of two different-sized wicks for the same burner. The intermediate portion of the tube is provided, as usual, with a plurality of slots 13, through which project the wick-operating wheels 14, that are carried by a stem 15, which projects at both ends beyond the burner and carries two 70 knurled disks 16, by which the stem may be operated.

The base-plate is provided with two aligned slots or orifices 17, that are adapted to be engaged by spring-fingers 18, carried by the 80 cone 19, which latter may be of the usual or any preferred construction, the fingers being removably engaged with the orifices 17, thereby to permit the cone to be reversed, according to which end of the wick-tube will be utilized.

Arranged on the side of the base-plate opposite the gallery 1 is a second gallery embodying a plurality of members 20, each of which consists of two elements connected by 90 a hinge-joint 21, one of each of the elements having fingers 23, that are adapted to engage orifices 22 in the base-plate and against which they are bent and secured, as at 23, and the other elements 24 being, if preferred, suitably 95 ornamented to present a neat and finished appearance to the article, as indicated by dotted lines in Fig. 1. These supplemental gallery members when the gallery 1 is engaged by the chimney are folded inward, and their free 100 ends are held combined with the collar 4 by engagement with the lugs or catches 25, so as to be out of the way and to give the burner the appearance of those in common use. As will be noted by reference to Fig. 1, the gallery members 20 are disposed within the circumference of the gallery 1, thereby to adapt them to accommodate a smaller chimney than the former gallery, it being understood, of course, that when the burner is reversed to 105 110

bring the smaller end of the wick-tube upward these foldable gallery members will be the means for holding the chimney.

The improvements herein described are simple in character, will be found thoroughly efficient in use for the purposes designed, and will prove highly convenient to householders, inasmuch as it frequently happens that a burner on one size of lamp gives out, and under such conditions the burner of this invention will be found of utility, as it may be made to perform the function of the one disabled.

Having thus described the invention, what is claimed is—

- 15 1. A lamp-burner embodying a reversible gallery-plate and a detachable cone.
2. A lamp-burner embodying a base-plate and fixed and foldable gallery members disposed on opposite sides thereof.

3. A lamp-burner embodying a base-plate and fixed and foldable gallery members disposed on opposite sides thereof and of different circumferences.

4. A lamp-burner embodying a base-plate, 25 fixed and foldable gallery members disposed on opposite sides thereof, and a detachable cone.

5. A lamp-burner embodying a base-plate, fixed and foldable gallery members combined therewith, collars of different diameters carried by the plate, and a wick-tube having its terminals of different transverse diameters.

In testimony that I claim the foregoing as my own I have hereto affixed my signature in 35 the presence of two witnesses.

CLIFTON I. MILLER.
